UNITED STATES PATENT OFFICE.

JOHN R. HILL, OF KNOXVILLE, TENNESSEE.

SIGNAL.

Application filed April 15, 1925, Serial No. 23,359. Renewed January 23, 1926.

To all whom it may concern:

Be it known that I, JOHN R. HILL, a citizen of the United States, residing at Knoxville, in the county of Knox and State of Tennessee, have invented new and useful Improvements in Signals, of which the following is a specification.

This invention relates to signals for railroad crossings and the like, the general object 10 of the invention being to provide means, actuated by a train or car, for notifying persons that a train or car is approaching the crossing.

Another object of the invention is to so 15 arrange the parts that the signal will be set in operative position by a train approaching the crossing and then returned to inoperative position as the train passes over the crossing.

20 A still further object of the invention is to make the device entirely mechanical and eliminate the use of all electrical appliances.

Still another object of the invention is to 25 make the device usable on a single track road with trains passing in both directions.

This invention also consists in certain 30 other features of construction and in the combination and arrangement of the several parts, to be hereinafter fully described, illustrated in the accompanying drawings and 35 specifically pointed out in the appended claims.

In describing my invention in detail, reference will be had to the accompanying 35 drawings wherein like characters denote like or corresponding parts throughout the several views, and in which:—

Figure 1 is a perspective view of a railroad track and a crossing.

40 Figure 2 is a section on line 2—2 of Figure 1.

Figure 3 is a sectional view through the base part of the signal device.

45 Figure 4 is a sectional view showing the latch means.

Figure 5 is a perspective view of the free end of one of the tread bars and showing its depending member in engagement with the latch member.

50 Figure 6 is a plan view showing one of the trip members.

Figure 7 is a section on line 7—7 of Figure 6.

55 In these views, A indicates the track and B the crossing which is to be protected by the signal C. This signal may consist of

the vertical shaft 1 having its lower end rotatably mounted in the base 2 and having at its top the signal arms 3 and the casing 4 for holding a lamp, two sides of the casing being closed and the other sides having windows 4' therein. These parts are so arranged that when the shaft is moved to a position with the arms at right angles to the crossing the rays of light from the lamp 60 can be seen through the windows and an opening is formed in the bottom of the casing so that some of the rays of light will illuminate the arms. Thus the signal can be thoroughly seen at night as well as during the day. When in inoperative position the shaft will be turned so that the arms will be parallel with the road or crossing and the blank sides of the casing will face the road, so that the signal parts cannot be seen by 65 a person on the road. A drum 5 is fastened to the lower end of the shaft 1 and is arranged within the base 2 and a spring 6 is connected with said drum and with a part of the base and tends to hold the shaft with 70 its signal parts in inoperative position. A horizontally arranged shaft 7 extends into the base and has a drum 8 on its outer end which is connected with the drum 5 by the chain 9 so that the movement of the shaft 7 75 will be communicated to the shaft 1 through the drums and chain. A drum 10 is connected with the other end of the shaft 7 and a spring 11 connects said drum 10 with a part of a casing 12 which encloses the inner 80 end of the shaft and the drum 10. This spring 11 tends to move the drum 10 and the shaft 7 in a clockwise direction and thus move the drum 5 and shaft 1 against the action of the spring 6 and to set the signal 85 parts in operative position. The casing 12 is placed on the track and the shaft 7 extends from this casing into the base 2 and said shaft is enclosed by a casing 12'. A pair of tread members 13 and 13' are 90 placed alongside the track adjacent the crossing, the members being pivoted to a part of the track at their outer ends and their inner ends are connected together by the slotted link 14 on the member 13' engaging the stud 15 on the member 13. Thus the movement 95 of one member will be communicated to the other. These members are preferably of angle iron and are placed alongside one of the rails of the track so that they will be engaged by the wheels of the train passing along the track and depressed by the weight 100 105 110

of the train. Brackets 16 may be provided for guiding the members in their movement and springs 17 are used for holding the members in raised position. The member 13 5 carries a depending part 18 at its free end which is connected by a chain 19 with the drum 10 on shaft 7 and said member has a shoulder 20 thereon which is adapted to be engaged by a latch bar 21 pivotally arranged 10 in the casing 12 and which has a spring 22 for holding it in latching position. Trips 23 and 23' are arranged an appreciable distance from the crossing, one at each side of the crossing, and these trips are connected 15 by the flexible members 24 with the latch bar 21. The member which connects the trip 23' with the latch bar has a chain part which passes over a pulley 25 in the casing 12 so that the latch bar will be moved in the 20 same direction when either member 23 or 23' is struck by a train. Each member is pressed outwardly against the rail by a spring 26 arranged in a casing 27 and each trip member has its edge, which faces the 25 crossing, beveled, as at 28, so that a train after passing the crossing and striking a trip member will simply move the trip member outwardly so that the wheel of the train will pass between the trip member and the 30 rail.

From the foregoing it will be seen that a train approaching the crossing will strike a trip member which will pull upon the flexible member 24 so that the latch 21 will be 35 moved away from the depending part 18 which will enable the spring 11 to partially rotate the drum 10 and the shaft 7 and this movement will be communicated to the shaft 1 through the drums 5 and 8 and the chain 40 9 and thus the signal parts will be moved to operative position, as shown in Figure 1. This movement will also raise the tread members 13 and 13' above the rail. This will indicate to persons on the road that a 45 train is approaching the crossing. Then when the train reaches the crossing it will strike one of the tread members and depress the same so that the depending part 18 will pass to a position where the latch 21 can 50 again engage the shoulder 20 to hold the tread members depressed after the train has passed and this downward movement of the tread members will also cause the chain 55 19 to partially rotate the drum 10 and the shaft 7 and permit the spring 6 to rotate the shaft 1 to a position where the signal parts will be in inoperative position. A train approaching the crossing from the opposite direction will operate the parts in a similar 60 manner.

It will be seen that I have produced an automatic crossing signal which is wholly mechanical in its action and which is rendered active by a train approaching the 65 crossing and inactive when the train passes

over the crossing. There are no parts to be attached to the train and no electrical appliances are used.

It is thought from the foregoing description that the advantages and novel features 70 of my invention will be readily apparent.

I desire it to be understood that I may make changes in the construction and in the combination and arrangement of the several parts, provided that such changes fall 75 within the scope of the appended claims.

What I claim is:—

1. A signal of the class described comprising a signal member, a train operated tread member, means for normally holding 80 the signal member in operative position and the tread member in raised position so that when the tread member is lowered by a train the signal will be moved to inoperative position, a latch member for holding the tread member in lowered position and a train operated trip member for moving the latch member to releasing position.

2. A signal of the class described comprising a signal member, a train operated tread member, a rotary member, flexible means connecting the rotary member with the signal member, flexible means connecting the rotary member with the tread member, yieldable means for normally holding the parts 95 in a position with the tread member raised and the signal member in operative position so that when the tread member is lowered by a train the signal will be moved to inoperative position, a latch member for holding the tread member in lowered position and a train operated trip member for moving the latch member to releasing position.

3. A signal of the class described comprising a vertically arranged shaft, signal means carried thereby, a horizontally arranged shaft, flexible means connecting the two shafts together, a train actuated tread member, flexible means connecting the same with the horizontal shaft, spring means for normally holding the parts in a position with the signal means in operative position and the tread member in raised position, a latch member for holding the tread member in lowered position and a train actuated trip member for moving the latch member to releasing position.

4. A signal of the class described comprising a vertically arranged shaft, signal means carried thereby, a horizontally arranged shaft, drums on the shafts, a flexible member connecting the drums together, a pair of train operated tread members, one of which has a depending part, a second drum on the horizontal shaft, a flexible member connecting said drum with the depending part, spring means for holding the parts in a position with the tread members raised and the signal means in operative po- 120 125 130

sition, a latch member engaging the depending part for holding the tread members in lowered position, a pair of train operated trip members and means for connecting said members with the latch member to move the same to releasing position when the trip members are operated by a train.

5. A signal of the class described comprising a signal carrying member, a pair 10 of train operated tread members, means for normally holding the tread members in raised position and the signal member in operative position so that when the tread members are lowered the signal member will

be moved to inoperative position, a latch 15 member for holding the tread members in lowered position, a pair of train operated trip members, means for connecting said trip members with the latch member so that the latch member will be moved to releasing 20 position when the trip members are actuated by a train and means for permitting a train to pass by the trip members without actuating the same when the train has 25 passed the crossing.

In testimony whereof I affix my signature.

JOHN R. HILL.
